VINE GUIDE

Richard P. Miller, Berkshire Heights, Pa.

Application October 31, 1932. Serial No. 640,537

2 Claims. (Cl. 47—46)

My invention relates generally to plant training and supporting means, and particularly to new and novel vine training and supporting guides for attachment to supports, such as walls, posts, 5 trellis, and the like, and an important object of my invention is to provide devices of this character which are inexpensive and efficient.

It is also an important object of my invention to provide devices of the character described 10 which can be readily placed and secured in a variety of positions on a support for carrying and guiding a vine thereon, and which will after installation securely hold and guide the vine without in any way constricting upon, or injuring the 15 fragile portions of the vine.

It is also an important object of my invention to provide devices of the character described which have portions to be bent around or into other holding relationship to the vines so as to securely 20 hold the vine in a variety of positions, which means may also be bent to release the vine therefrom without requiring removal of the devices from the support to which they were attached.

Other objects and advantages of my invention 25 will be apparent from a reading of the following description in connection with the drawing, wherein for purposes of illustration I have shown a preferred embodiment of the invention.

In the drawing:—

30 Figure 1 is a general view showing a portion of a brick wall, and a vine supported thereon by means of a plurality of the devices of my invention.

Figure 2 is a side elevational view of one of the 35 devices installed on the wall.

Figure 3 is a perspective view of one of the devices.

Figure 4 is a perspective view of the bendable portion of the device minus the base portion 40 thereof.

Figure 5 is a perspective view of one of the devices shown with the bendable portion thereof bent into one of the positions for holding a vine.

Referring in detail to the drawing the numeral 45 5 refers generally to a supporting surface such as a wall, post, trellis, or the like to which is adapted to be attached one form of the invention which is generally designated by the numeral 6.

The combination support and guide 6 comprises 50 a disk-like base 7 which, for convenience, may be generally frusto-conical in form as shown in the drawing. This formation constitutes a small axial face 8 and a large axial face 9 and the beveled wall 10. The base may be formed of any 55 suitable material, such as ceramic material of

the glazed or unglazed type, or of any suitable composition which provides a fairly light-weight cementable base which will not readily deteriorate under the action of the elements, and which is capable of being formed or molded so as to receive 60 and hold therein the bendable member of the device. In applying the device of the invention to a wall or other supporting surface, the large face 9 is prepared with a coating of a suitable cementing material adequate to cement the base 65 to the face of the supporting medium and the prepared large face 9 is then pressed against the surface of the supporting medium to which the device is to be attached with sufficient pressure to accomplish a bond therebetween. If desired, 70 the coating of cementing material may be placed on the surface of the supporting medium instead of upon the base 7 of the guide device with similar results. There are various cements on the open market which are suitable for this purpose, 75 a quick drying, strong cement being recommended.

It is to be observed that by the provision of the base 7 and the method of attaching the same to the supporting medium by means of the coating of cement 11, the necessity to bore, chisel, or otherwise work upon and force objects into the surface of the supporting medium is dispensed with, and injury to such supporting medium is avoided. Whenever the devices of the 80 invention are removed from the supporting medium, the place on the supporting medium where the device was attached may be readily rendered inconspicuous or entirely eliminated, so as to 85 avoid marring the appearance thereof. It will 90 be obvious that the device of the invention may be colored to match or blend with the color of the supporting medium or of the plants to be supported, so that they will be inconspicuous or decorative, as desired.

The bendable member 6 of the device of the invention comprises a hairpin form such as that shown in Figure 4, which is made of suitable bendable metal, which will be susceptible of repeated bendings without fracture, and which 95 will maintain the form into which it may be bent, after bending.

It will be observed that the legs of the hairpin form are brought close together into touching relation and that they are given a waved form 100 as indicated at 12, so that the waved portions coact with each other, the waves of one leg being substantially conformed to the waves of the other leg. The terminal end portions of the legs are laterally bent as indicated at 13, and on the ends 105 110

of these portions are angularly directed flattened portions 14.

The base 7 is cast, molded, pressed or otherwise formed upon the portions 13, 14 of the legs of the bendable member 6 so that when the base is finished, the portions 13, 14 will be embedded therein as shown in Figure 2 in dotted lines, so as to unite the base 7 and the bendable member 6.

Reference to Figure 5 shows how one of the devices may be bent to confine and support thereon a portion of a vine. Though a bend is shown at 15 in the bendable member 6, the bendable member may be bent at any other point so that a portion thereof is directed in a desired direction. It is to be observed that there is imposed no limitation upon the directions which the bendable member may take with respect to vertical and horizontal planes, but any disposition may be made thereof, and any bend placed in the bendable member 6, which may suit the convenience and fancy of any person employing the same. Several different directions of the bendable member are indicated in Figure 1.

Though I have shown and described herein a preferred embodiment of the invention, it is to be definitely understood that I do not desire to limit the application of the invention thereto, and any change or changes may be made in material and structure and arrangement of parts, within the spirit of the invention and the scope of the subjoined claims.

What is claimed is:

1. A device of the character described comprising a base permanently cementable to a supporting surface, a hook member having laterally

directed portions embedded in the base so that the hook member extends on one side of the base only, said hook member being arranged to be readily bendable into a form to hold and guide a portion of a plant relative to the supporting surface, said base being relatively small and thick and frusto-conical in form, said hook member having a portion projecting axially from one end of the base, said bendable hook member comprising a U-shaped loop arranged with a portion of its legs axially entering the said one end of the base, laterally directed portions on the legs within and embedded in the base and acting as anchors.

2. A device of the character described comprising a base permanently cementable to a supporting surface, a hook member having laterally directed portions embedded in the base so that the hook member extends on one side of the base only, said hook member being arranged to be readily bendable into a form to hold and guide a portion of a plant relative to the supporting surface, said base being relatively small and thick and frusto-conical in form, said hook member having a portion projecting axially from one end of the base, said bendable hook member comprising a U-shaped loop arranged with a portion of its legs axially entering the said one end of the base, laterally directed portions on the legs within and embedded in the base and acting as anchors, the legs of the hook member being brought close together and parallel and having mutually conforming longitudinal waves therein whereby the legs mutually support each other and even bending thereof facilitated.
